(57) **CLAIM**

The ornamental design for a display screen with icon, as shown and described.

DESCRIPTION

FIG. 1 illustrates the display screen with a static first icon according to a first embodiment of the claimed design; and, FIG. 2 illustrates the display screen with the static first icon according to a second embodiment of the claimed design. The broken lines in the drawings depict portions of the display screen with icon that form no part of the claimed design. The different stippling patterns within the icons illustrate areas of contrasting appearance.
